US00D452694B1

(12) **United States Design Patent** (10) **Patent No.:** **US D452,694 S**
Irie (45) **Date of Patent:** **** Jan. 1, 2002**

(54) **CATALYTIC CONVERTER**

(75) Inventor: **Tohru Irie**, Nishikamo-gun (JP)

(73) Assignee: **Sango Co., Ltd.**, Nagoya (JP)

(**) Term: **14 Years**

(21) Appl. No.: **29/112,023**

(22) Filed: **Oct. 12, 1999**

(30) **Foreign Application Priority Data**

(57) **CLAIM**

The ornamental design for catalytic converter, as shown and described.

DESCRIPTION

FIG. 1 is a top view of a first embodiment of the catalytic converter;

FIG. 2 is a front view thereof, the rear view being a mirror image;

FIG. 3 is a bottom view thereof;

FIG. 4 is a left side view thereof;

FIG. 5 is a right side view thereof;

FIG. 6 is a top view of a second embodiment of the catalytic converter;

FIG. 7 is a front view thereof, the rear view being a mirror image;

FIG. 8 is a bottom view thereof;

FIG. 9 is a left side view thereof;

FIG. 10 is a right side view thereof;

FIG. 11 is a top view of a third embodiment of the catalytic converter;

FIG. 12 is a front view thereof, the rear view being a mirror image;

FIG. 13 is a bottom view thereof;

FIG. 14 is a left side view thereof;

FIG. 15 is a right side view thereof;

FIG. 16 is a top view of a fourth embodiment of the catalytic converter;

FIG. 17 is a front view thereof, the rear view being a mirror image;

FIG. 18 is a bottom view thereof;

FIG. 19 is a left side view thereof, the right hand side being a mirror image;

FIG. 20 is a top view of a fifth embodiment of the catalytic converter;

FIG. 21 is a front view thereof, the rear view being a mirror image;

FIG. 22 is a bottom view thereof;

FIG. 23 is a left side view thereof; and,

FIG. 24 is a right side view thereof.
